Fig. 7

Fig. 8

FIG. 1 is a perspective view of the twin spinner blades of the present invention;

FIG. 2 is a perspective view similar to FIG. 1 showing the elements in a different position during use;

FIG. 3 is a plan view of the blade of FIGS. 1 and 2;

FIG. 4 is a plan view similar to FIG. 3 showing the elements in a different position;

FIG. 5 is an end view looking at the leading end of the twin spinner blades of the preceding figures;

FIG. 6 is an end view looking at the trailing end of the twin spinner blades of the preceding figures;

FIG. 7 is a perspective view similar to FIG. 1, but showing a modified form of the invention; and

FIG. 8 is a perspective view similar to FIG. 2, but showing the modified form of the invention as shown in FIG. 7.

I claim:

The ornamental design for twin spinner blades, as shown and described.
